UNITED STATES PATENT OFFICE.

HERBERT HARRIS HOOSE, OF PORT CHESTER, NEW YORK.

MOLDING-MACHINE.

1,072,229.

Specification of Letters Patent. Patented Sept. 2, 1913.

Application filed August 31, 1912. Serial No. 718,059.

To all whom it may concern:

Be it known that I, HERBERT H. HOOSE, a citizen of the United States, and a resident of Port Chester, in the county of Westchester and State of New York, have invented 5 a new and Improved Molding-Machine, of which the following is a full, clear, and exact description.

This invention relates to molding machines, and particularly to an improvement 10 in the art wherein the engagement between the roller and the sand contained in the flask is a positive one, that is, the pressure brought to bear on the same is not due merely to the weight of the roll; means are 15 provided for turning the roll and moving the flask with the sand therein positively so that the mere frictional engagement between the parts is not relied upon.

20 A further object of the invention is the provision of a pivoted member which I term a scraper, which is used to remove a surplus of sand before the flask is passed under the roll, and also to thoroughly remove any 25 loose sand from the mold after the same has been passed thereunder.

Further objects and advantages of the invention are not specifically set forth at the present time but will appear as the 30 description proceeds.

Reference is to be had to the accompanying drawings forming a part of this specification, in which like characters of reference indicate corresponding parts in all the 35 views, and in which—

Figure 1 is a side view of the molding machine; Fig. 2 is a vertical sectional view showing the roll having a portion thereof in engagement with the sand used in forming 40 the mold; Fig. 3 is a vertical sectional view through the roll and the mold; Fig. 4 is a plan view of the machine; while Fig. 5 is a sectional view on the line 5—5 of Fig. 4.

The machine comprises any suitable bed 1 45 supporting a longitudinally movable table 2 which has a rack 3 on its under side, there being rollers 4 between the table and the bed in order to provide for smooth running. The table is adapted to support any suitable 50 flask 5 containing a quantity of sand 6, and also patterns from which the molds are to be made; it is to be noted that opposite sides of the bed are provided with standards 7 extending above the table, the flask and the sand. Extending transversely of the bed is 55 a shaft 8 having a driving pulley 9 at one

end thereof and a gear 10 around which a chain 11 passes, this chain being used in positively turning or driving the roll 12 to be presently described. Also mounted on 60 this shaft 8 is a pinion 13 meshing with a gear 14 suitably supported by the bed, which gear meshes with the said rack 3 on the under side of the table 2, whereby as the shaft 8 is turned the table will be moved 65 forwardly along the said bed. Extending longitudinally of the said standards 7 are screws 15, the upper ends of which are provided with bevel gears 16, the lower threaded ends of the screws engaging in blocks 17 70 carried by the bearings 18 which support the said roll 12 by means of the shaft 19. Extending transversely of the standards is a shaft 20 having squared ends 21 by which it may be conveniently turned, the shaft 75 75 being provided with a plurality of bevel gears 22 meshing with the above-mentioned gears 16, the purpose of which is to raise and lower the roll 12 relatively to the table 2. 80

While the particular form of the roll and the bearings therefor may be widely changed it is to be noted that one end of the shaft 19 on which the roll is mounted is provided with a gear 23 around which the above-mentioned chain 11 passes, so that this roll is positively driven, and being driven from the same source of power as the table 2, it will be apparent that a timed relation exists between the travel of these parts. The roll 90 shown in the drawings is preferably a hollow cylindrical body having a number of projections 24 on its outer side, which projections are adapted to come into forcible engagement with the sand 6 contained in the flask 5, when the machine is operating, at certain portions thereof, thereby bringing greater pressure to bear at these portions and compressing the sand, as is indicated at 95 6^a in Fig. 2; these compressed portions may 100 be located where desired, in which event the particular form of the roll 12 will vary, depending on the particular form of molding to be provided. In any event the roll is positively driven as mentioned, and pressure 105 brought to bear is not due merely to the weight of the roll, but is due to the fact that the roll is held in the bearing 18 immovably, and that if the parts are to continue their relative movement such compression of the sand must follow. 110

The particular form of the various ele-

ments described is immaterial as far as the performance of the inventive idea is concerned. It is obvious, of course, that such features as size and shape of the various parts may differ greatly in different machines, all of which embody the same inventive idea.

In order to insure the proper amount of sand in each flask, and not any more than such amount, I propose to use a suitable device which I term a scraper, operating in advance of the roll 12, and the purpose of which is to remove all sand save a certain amount. Referring particularly to Figs. 1 and 4, it will be noted that this scraper is essentially a rectangular element 30, the opening in which is sufficient to pass around the roll 12, the sides of the body on opposite sides of the roll performing the scraping function as indicated in Fig. 1. The ends of this element are preferably provided with suitable stub shafts 31 mounted in suitable bearings 32, which bearings are carried by oppositely extending bolts 33 carried by the standards 7, so that movement of the bolts upwardly or downwardly will result in raising or lowering this scraper relatively to the bed, and providing for the removal of more or less surplus sand. As shown in Fig. 1, the left side of the scraper is engaging the sand 6 in the flask 5 at a certain elevation, the sand extending above this elevation being removed or prevented from passing beneath the roll 12, as will be apparent; the opposite side of the scraper lies closely ad-

jacent the top of the flask 5^a which has already passed under the roll, and removes any further loose sand which may be lying on top. It will be obvious that the use of such a scraper permits the sand to be indiscriminately thrown into the flask before the same is placed on the bed preparatory to passing beneath the roll, such operation materially reducing the cost of forming the mold. It is, of course, obvious that the scraper while shown adjustable longitudinally of the standards 7, may also be adjusted in order to extend at various angles from the said standards to vary the amount of sand removed from the flask just entering under the roll.

Having thus described my invention, what I claim as new and desire to secure by Letters Patent is:—

The combination of a table adapted to support a flask containing sand, a roll positioned above the flask, and a scraper comprising a rectangular element having portions positioned on opposite sides of the roll, the said portions being adapted to engage and remove some of the sand in the flask both before and after the flask passes beneath the roll.

In testimony whereof I have signed my name to this specification in the presence of two subscribing witnesses.

HERBERT HARRIS HOOSE.
